UNITED STATES PATENT OFFICE.

WALTHER BOSHECK, OF PLAUE, GERMANY, ASSIGNOR TO THE FIRM: VOGTLANDISCHE MASCHINENFABRIK (VORMALS: J. C. & H. DIETRICH) AKTIENGESELLSCHAFT, OF PLAUE, GERMANY.

SHUTTLE-BOX-SELECTING MECHANISM FOR SHUTTLE BOXES WITH MORE THAN TWO COMPARTMENTS.

Application filed March 19, 1924. Serial No. 700,239.

To all whom it may concern:

Be it known that I, WALTHER BOSHECK, a citizen of the German Republic, and a resident of Plauen, Saxony, Germany, have invented certain new and useful Improvements in Shuttle-Box-Selecting Mechanism for Shuttle Boxes with More Than Two Compartments, of which the following is a specification.

10 There are known change-box mechanisms for looms in which the change of the shuttle boxes is initiated by a catch-tooth shiftably arranged in a lifting wheel and adapted to be re-adjusted by a cam disk arranged co-
 15 axially with respect to said lifting wheel and adapted to be turned to and fro. With the known devices of this kind the forward and rearward movement of the cam disk is distributed over working phases, or upon a
 20 plurality of working cycles respectively, and every partial oscillation then corresponds to a corresponding re-adjustment of the shuttle box, in consequence whereof it is necessary to provide in the lifting wheel two separated
 25 catch-teeth which must be moved, firstly, always oppositely to one another, and secondly, both outwards and both inwards in alternation in certain intervals of time. This manner of operation necessitates the provision
 30 of two cam-disks constituting a double eccentric, but as this arrangement and combination of parts renders the device by far too complex, it has not been used practically. The same is true of another constructional
 35 form of the change-box in which the cam disk is carried round by the eccentric wheel at every partial rotation whereby it is rendered necessary to lock said disk at said wheel temporarily with the aid of springs; this entails fractures of the springs and diminishes the reliability of the service.

The object of my invention is to obviate the drawbacks above disclosed, and it attains that object in general by turning the cam disk back into its initial position after every cycle of the working phases. More especially, said object is attained by certain

arrangements and combinations of parts as described hereinafter and shown by way of example in the accompanying drawing. 50 Turning the cam disk back into its initial position after every cycle can be effected very reliably by a simple system of levers which undergoes nearly no wear and tear and requires only a very small force for being adjusted, or re-adjusted respectively. Besides, two or more lifting eccentrics can be assembled in a very simple manner upon a common shaft with the appertaining change-position devices for the catch-teeth, 60 in such a manner, that said eccentrics engage one another, whereby it is rendered possible to assemble an installation for change-boxes with 4 or 6 cells on an extraordinarily small space. 65

On the drawing Figure 1 is a side view of a loom provided with the improved shuttle change-box; Figure 2 is an axial section through the lifting wheel and Figure 3 a front view thereof; Figure 4 is a side view of the cam disk and Figure 5 a front view thereof; Figure 6 is a side view of the catch-tooth and Figure 7 a front view thereof; Figure 8 is an axial section through a plurality of eccentrics engaging one another and 75 Figure 9 is a side-view thereof, together with a bell-crank lever.

Referring to Figure 1 (righthand half), 15 denotes the frame of the loom in which are supported upright arms 16 carried by pivots 15^a located at their lower ends and carrying at their upper ends the lathe 16' which is combined with two shuttle boxes 17, of which one is arranged at one end or side, the other at the other end or side of said lathe. Each shuttle box has a plurality of cells. In the constructional form shown by way of example each shuttle box has four cells, and each is connected movably and adjustably by a guide-rod 18 and a connecting member 19 with the arm 20 of a bell-crank lever 20/21 carried by a pivot 20^a affixed to the frame 15. The arm 21 of this lever is connected with the arm 23 of an-

other bell-crank lever 23/24 by means of a rod 22. This bell-crank lever is also carried on a pivot or bolt 25 affixed in the frame of the machine. The arm 24 of the bell-crank lever 24/23 is connected with the crank-guide 9, the upper end of which is devised to form an eccentric ring 26 encompassing an eccentric 3 located loosely upon another eccentric 2 carried loosely by a horizontal shaft 12. The two eccentrics 2 and 3 can be adjusted relatively to one another in four different positions, as will be described later on, and corresponding to these four positions the shuttle-box 17 will be lifted or lowered by the mechanism consisting of the crank-guide 9, the bell-crank lever 24/23, the rod 22, the bell-crank lever 21/20, the connecting member 19, and the rod 18, that lifting and lowering taking place in such a measure that any one of the cells of the shuttle-box can be adjusted in proper height with respect to the path of the lathe.

The eccentric 2 is connected firmly with a disk 1 on one side thereof; the other side of the said disk is provided with two toothed segments 27. These segments are circularly curved, and separated from one another by two diametrically located gaps. Between said segments, in their plane, a practically circular member 8^a (Figs. 6 and 7) is located; this member is provided with two oppositely located teeth 8, and encompasses the cam disk 7 which is supported loosely rotatable upon the shaft 12, or upon the hub 6 of the disk 1 respectively. The inner shape of the cam disk 7 is accommodated to the member 8^a in such a way that the sum of the radii $a+b$ lying in a straight line is always equal to the distance c of those points of the member 8^a which are, or come, in contact with said cam disk 7. The member 8^a is conducted securely and reliably in this way by the cam disk 7.

In order to render it possible to re-adjust the cam disk 7 in a secure and reliable manner it is connected rigidly with the disk-like guide-plate 28, which is connected by a pivot 29 with a rod 30, the other end of which is jointed to the arm 31 of the double-armed lever 31/33 which is supported on the pivot 32 inserted into the frame of the machine. The arm 33 of this lever is subjected to the action of a spring 34 and carries the sinker 35 which is hinged to it and can be re-adjusted by means of a pull-wire in known manner relatively to a drive-plate 37, as determined by a jacquard-card. This plate is being reciprocated continually by known means, and is also lifted and lowered by a feeler 38 supported on the rim of the disk 1 which is of known configuration.

The shaft 12 is arranged parallelly to the uniformly rotating driving shaft 10 which forms an extension of the known crank shaft by means of which the lathe-carrying arms

16 are swung to and fro. Secured to the shaft 10 are the toothed segments 11, the teeth of which can be caused to gear with the toothed segments 27. This takes place when the sinker 35 has been re-adjusted by the jacquard device in such a manner that it is taken along by and with the drive-plate 37 when this performs its next forward movement, as simultaneously therewith the disk 28 is re-adjusted together with the cam disk 7, and the tooth 8 of the member 8^a is being moved into the path of the toothed segment 11, in consequence whereof this latter when being further turned carries the tooth 8 along with it and gets into gear with one of the toothed segments 27, whereafter the drive plate 37 is moved rearwards, whereas the lever 31/33 and, simultaneously therewith, the disk 28 and the cam disk 7 are moved back into their position of rest, the tooth 8 being shoved during that time out of the path of the segment. This having taken place, the segment 11 cannot cause any further turning of the disk 1 until the sinker 35 has again been re-adjusted. But when another rotation of the disk has been initiated it will be turned by the toothed segment only for an angle of 180° whereby a corresponding re-adjustment of the shuttle-box 17 is effected.

In the same manner as already described with respect to the eccentric 2, also the eccentric 3 can be re-adjusted by a disk 5 which is, however, not rigidly connected with said eccentric as it must be shiftable radially relatively to the disk 5 corresponding to the adjustments of the eccentric 2. The eccentric 3 is provided, for this reason, with a pivot 4 engaging a radial slot of the disk 5 so that the eccentric 3 can be turned by the disk 5 in perfectly reliable manner. Corresponding to the disk 1 the disk 5 is provided with two toothed segments 27', and between these latter is provided another shiftable tooth 8' which is subjected to the action of a cam disk 7' supported loosely upon the hub of said disk 5 and provided with a guide-plate 28'. Also this plate is acted on by a jacquard device just as has been described with respect to the plate 28.

As long as the shuttle-box is not to be re-adjusted, the eccentrics 2 and 3 must be retained in that position they occupy at the time being. This is effected by the teeth 8 and 8', as well as by a fixing lever 39 supported loosely upon the pivot 40 inserted into the frame of the machine; said lever is pressed against the toothed segments 27 by means of a spring 41. Two noses 42 are provided at the upper part of the lever 39; they get at the proper time into the path of the tooth 8 and cause that this latter is moved into the space or gap existing between said noses; the tooth is moved, however, out of that space or gap by means of the cam disk 139

7 when the opposite tooth is so shifted as to get into the path of the toothed segment 1.

I claim:

1. A shuttle change-box mechanism for 5 looms, comprising in combination, a lifting-wheel, a member located in said wheel and having two oppositely located teeth forming catch-teeth, and a cam disk adapted to be turned alternately forward and rearward, 10 and means adapted to turn said cam-disk back into its initial position after the completion of every cycle of operations, substantially as set forth. 15
2. A shuttle change-box mechanism for 15 looms, comprising, in combination, a lifting-wheel, a member located in said wheel and having two oppositely located teeth forming catch-teeth, and a cam disk adapted to be turned alternately forward and rear- 20 ward; a jacquard-device, a sinker, and a drive-plate, these parts being combined in such a manner that the combination is adapted to turn said cam disk in correspond- 25 ence with the pattern of said jacquard de- vice; and a spring so arranged as to be adapted to turn said cam disk back into its initial position after the completion of every cycle of operations, substantially as set forth. 30
3. A shuttle change-box mechanism for 30 looms, comprising in combination, a lifting-wheel, a member located in said wheel and having two oppositely located teeth forming catch-teeth, and a cam disk adapted to be turned alternately forward and rear- 35 ward; a jacquard-device, a sinker, and a drive-plate, these parts being combined in such a manner that the combination is adapt- 40 ed to turn said cam disk in correspondence with the pattern of said jacquard device; a feeler arranged to contact with the rim of said lifting wheel and to lift and lower alternately said drive-plate after every semi- 45 rotation of the lifting wheel and to cause it to contact with said lifter only when another semi-rotation of the lifting wheel and another re-adjustment of the box is to take place, substantially as set forth. 50
4. A shuttle change-box mechanism for 50 looms, comprising, in combination with the shuttle-boxes, rods connected with the shuttle-box cells and rods connected with said first-mentioned rods; eccentrics located upon a common shaft and being arranged one within the other and adapted to support and 55 re-adjust the rods mentioned in the second place; wheels connected with said eccentrics and being supported upon the shaft of the same; rotary members having each opposite- 60 ly located catch-teeth and being arranged in said wheels; and cam-disks so arranged as to be adapted to re-adjust said members; and means adapted to turn said cam-disk back into its initial position after the completion of every cycle of operations, sub- 65 substantially as set forth. 70
5. A shuttle change-box mechanism for 75 looms, comprising, in combination with the shuttle-boxes, rods connected with the shuttle-box cells, and rods connected with said first-mentioned rods; eccentrics located upon a common shaft and being arranged one within the other and adapted to support and re-adjust the rods mentioned in the second place; wheels connected with said eccen- 80 trics and being supported upon the shaft of the same; rotary members having each opposite- 85 ly located catch-teeth and being arranged in said wheels; and cam-disks so arranged as to be adapted to re-adjust said members; a jacquard-device, a sinker, and a drive-plate, these parts being combined in such a manner that the combination is adapted to turn said cam disk in correspond- 90 ence with the pattern of said jacquard de- vice; and a spring so arranged as to be adapted to turn said cam disk back into its initial position after the completion of every cycle of operations, substantially as set forth. 95
6. A shuttle change-box mechanism for 95 looms, comprising, in combination with the shuttle-boxes, rods connected with the shuttle-box cells, and rods connected with said first-mentioned rods; eccentrics located upon a common shaft and being arranged one within the other and adapted to support and re-adjust the rods mentioned in the second place; wheels connected with said eccen- 100 trics and being supported upon the shaft of the same; rotary members having each opposite- 105 ly located catch-teeth and being arranged in said wheels; and a cam-disk adapted to be turned alternately forward and rearward; a jacquard-device, a sinker, and a drive-plate, these parts being combined in such a manner that the combination is adapt- 110 ed to turn said cam disk in correspondence with the pattern of said jacquard-device; substantially as set forth. 115
7. A shuttle change-box mechanism for 115 looms, comprising, in combination with the shuttle-boxes, rods connected with the shuttle-box cells, and rods connected with said first-mentioned rods; eccentrics located upon a common shaft and being arranged one within the other and adapted to support and re-adjust the rods mentioned in the second place; wheels connected with said eccen- 120 trics and being supported upon the shaft of the same; rotary members having each opposite- 125 ly located catch-teeth and being arranged in said wheels and cam-disks so arranged as to be adapted to re-adjust said members; and a cam-disk adapted to be turned alternately forward and rearward; a jacquard-device, a sinker, and a drive-plate, these parts being combined in such a manner that the combination is adapted 130

to turn said cam disk in correspondence with the pattern of said jacquard device; a feeler arranged to contact with the rim of said lifting wheel and to lift and lower alternately said drive-plate after every semi-rotation of the lifting wheel and to cause it to contact with said lifter only when an-

other semi-rotation of the lifting wheel and another re-adjustment of the box is to take place, substantially as set forth. ¹⁰

In testimony whereof I affix my signature.

WALTHER BOSHECK.
